OR D 11,292

No., 11,292

July 8, 1879

UNITED STATES PATENT OFFICE.

WILLIAM J. WALKER, OF CAMDEN, NEW JERSEY, ASSIGNOR TO HENRY C. TUCKER, OF PHILADELPHIA, PENNSYLVANIA.

DESIGN FOR A DIE FOR STAMPING CHECKS AND DRAFTS.

Specification forming part of Design No. **11,292**, dated July 8, 1879; application filed June 2, 1879.
[Term of patent 3½ years.]

To all whom it may concern:

Be it known that I, WILLIAM J. WALKER, of the city and county of Camden, and State of New Jersey, have originated and designed a new and useful Design for Die for Stamping Checks, Drafts, &c., of which the following is a full, clear, and exact description, reference being had to the accompanying illustration, making part of this specification.

My design consists of a series of six-pointed stars, which are united one to the other in such manner that each star is formed by the points of the contiguous stars, except it may be the outer rows.

In the center of each star is a trefoil or three-winged figure.

It will be seen that I present a neat and tasty design.

What I claim as my invention is—

1. The design for die for stamping checks, drafts, &c., the same consisting of a series of connected six-pointed stars, each star thereof being formed by the points of the contiguous stars, as shown and described.
2. In a design for die, the trefoils or three-winged figures in the center of the stars, as shown and described.

WILLIAM J. WALKER.

Witnesses:

JOHN A. WIEDERSHEIM,
A. P. GRANT.
